UNITED STATES PATENT OFFICE

2,523,862

SAFETY CLOTHESLINE SUPPORT

Joseph A. Cadrain, New Britain, Conn.

Application March 21, 1946, Serial No. 655,938

1. Claim. (Cl. 211—119.07)

1

This invention relates to clothesline, and more particularly to an apparatus including a support for the clothesline pulley located at the house end of the clothesline to permit said pulley to be swung inside a house or verandah so that the clothes may be loaded on the lower stretch of the line without the necessity for the laundress to lean out into a dangerous position.

One object of the present invention is to provide a pair of small auxiliary pulleys mounted on the swinging support around which the clothesline is passed in order to maintain a constant tension in the clothesline irrespective of whether the swinging pulley is located inside or outside the house.

A further object is to provide means for preventing the lower stretch of the line from swinging out the window without first hooking the line over the lower auxiliary pulley.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawings,

Fig. 1 is a side view of the clothesline apparatus upon which the present invention has been installed, and showing in full lines the swinging arm located inside the house, and in dotted lines the position of the arm when extending outside the house.

Fig. 2 is a top plan view of the same, showing an alternative position of the clothesline when it is located in an inclined position.

Fig. 3 is a rear view on a larger scale of the resilient hinge for connecting the adjustable support to the house frame.

Fig. 4 is a fragmentary top plan view of the hinged support for the swinging arm with the latter shown outside of the house.

Fig. 5 is a side view of the same showing the relative location of the upper and lower auxiliary pulleys.

Referring now to the drawings in which like reference numerals denote corresponding parts throughout the several views, the numeral 10 indicates a horizontal telescopic swinging arm, preferably square in cross section, which is pivotally connected to the left hand of a window frame H of a house. The telescopic arm 10 comprises an inner section 11 and an outer section 12, con-

2

nected together in adjusted position by a locking bolt 13 which may pass through any pair of a series of opposed holes 13a located in the sides of the outer section 12.

5 A clothesline 15 is adapted to be mounted upon a pair of vertical pulleys indicated by the numerals 14 and 31, as shown in Figs. 1 and 2. The pulley 14 is designated as the "house" pulley, and the pulley 31 as the distant pulley, the latter being conveniently located on a pole X in the backyard.

10 The section 11 of the arm 10 is pivotally mounted upon a vertical pivot pin 16 supported in a pair of horizontal guide flanges 17, 18 forming part of a pair of channel bars 19, 20 secured as by rivets 20a to a small square vertical plate 21. The plate 21 is secured in flat contact with a hinge plate 22 which is connected to a similar hinge plate 23 by a vertical hinge pin 24. The hinge pin 24 is provided with an upper head and a lower nut 25, as shown.

15 In order to provide resiliency for the hinge plate 23, provision is made of a pair of inclined slots 26, 27, as clearly shown in Fig. 3 whereby when the nut 25 is tightened the hinge plates 22, 23 will be locked tightly together. The hinge plate 23 is also provided with a pair of outer looped eyes 28, 29 and the hinge plate 22 with a single inner looped eye 30, all of which eyes embrace the hinge pin 24, as clearly shown in Figs. 3 and 5 of the drawing.

20 In order to permit the "house" pulley 14 to be pulled inside the window of the house for convenience and safety in loading the clothesline with clothes C, provision is made of a pair of auxiliary small pulleys 32, 33 mounted on vertical pivot pins 34, 35.

25 Mounted on the horizontal flange 18 of the lower channel bar 20 is a leaf spring 36 provided with a pair of curved end manipulating tongues 37, 38 depending therefrom, and having snap locks 39, 40 extending upwardly therefrom for passing through apertures 41, 42, in said horizontal flange 18, and adapted to selectively engage in a socket 43 formed in the lower edge of the swinging arm 10.

30 Provision is also made of a lock rod 44 connected to a chain 45 having at its upper end a ring 46 attached to said rod 44, said rod having an enlarged handle 47 adapted to seat upon the channel bar flange 17.

35 A shoulder 48 formed at the lower end of the handle 47 permits said handle to rest upon the upper surface of the flange 17 with the lower end

of said lock rod extending through holes 49, 50 in the flanges 17, 18, respectively.

The lower end of the chain 45 is adapted to be attached to the channel bar 20 by means of an apertured finger 51 and a screw 52. In order to permit a slight amount of vertical rocking of the arm 10 the channel bars 19 and 20 are connected to the hinge plate 21 by means of loosely fitted bolts 53, as clearly shown in Fig. 5 of the drawing.

In order to insure that the lower stretch of the line 15 upon which the clothes are hung will not swing out of the window without hooking the line over the lower auxiliary pulley 33, provision is made of a depending rod 54, as clearly shown in the drawing.

Operation

In operation the clothesline 15 will first be threaded through the "pole" pulley 31 located at a point distant from the house. The upper stretch of the line will then be passed around the top of the upper auxiliary small pulley 32 then around the top of the large "house" pulley 14 which is mounted in the free end of the swinging arm 10.

The line will then pass around the lower auxiliary pulley 33, and then back to the bottom of the distant pole pulley 31. Any desired type of line tightener or fastener P may be employed to connect the ends of the clothesline.

One advantage of the adjustable hinge support of the present invention is that it permits the line to pass directly to the house pulley from the pole without contact with the frame of the house, thus reducing friction on the pulleys. The arm 10 will be held detachably in either of its inside or outside positions by means of the snap lock pins 39, 40, which are adapted to engage selectively in the socket 43 in said arm.

It will be understood that if desired the clothesline pulley support may be reversed from the position herein shown if it should be desired to attach it to the right hand of a window frame, it only being necessary for this purpose to remove the four bolts 53.

While there has been disclosed in this specifi-

cation one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In a safety clothesline apparatus, a support plate, a hinge for securing said support plate to a wall of a house or other structure, an elongated arm pivotally secured at one end to said support plate, a large pulley secured on the free end of said arm, a pair of smaller upper and lower auxiliary pulleys secured to said support plate, a clothesline passing around said upper auxiliary pulley and said large pulley when the latter is swung within the confines of said house for loading, and passing around said lower auxiliary pulley only when said large pulley is swung outside said house for drying the clothes on the line, and a resilient flat leaf spring connected at its center to said support plate, said spring being provided with snap lock means on its extremities to selectively engage means mounted on said support plate to detachably latch said arm in either of its extreme positions.

JOSEPH A. CADRAIN.
